UNITED STATES PATENT OFFICE.

JOSEPH R. MAHAN, OF TOLEDO, OHIO, ASSIGNOR TO THE NATIONAL SUPPLY COMPANY, OF TOLEDO, OHIO, A CORPORATION OF OHIO.

POLISHED-ROD GRIP.

Application filed December 24, 1926. Serial No. 156,856.

My invention relates to polished rod grips which are devices for connecting the polished rods of a well pumping apparatus to the reins or other means that are reciprocated by one end of a walking beam or the like.

The principal object of this invention is to provide a polished rod grip with trunnions and reins which may be connected and disconnected without the use of any extra 10 tool or apparatus.

Referring to the accompanying drawing, Fig. 1 is a perspective view of my polished rod grip to which are attached a portion of two reins and a portion of a polished rod. 15 Fig. 2 is an edge view of Fig. 1. Fig. 3 is a central vertical section of Fig. 1, the section including the screws 4, the rod 3 and the nuts 5 being in elevation.

On the drawing, 1 designates the body of 20 the grip which is preferably made of a single piece of steel provided with a central longitudinal hole 2 containing the polished rod 3 which is clamped in the hole 2 by the two clamps 11 in the form of screw-eyes. 25 The eyes 12 of the clamps received the rod 3 and are slideable transversely of the rod in the slots 13 in the body 1. The screws 4 integral with the eyes 12 project through the holes 15 in the body 1 and have thereon the 30 nuts 5 which bear on the outer face of the body and draw the eyes into tightly gripping engagement with the rod 3.

The body 1 is also provided with two trunnions 6 extending from the opposite edges 35 of the body 1 at right angles to the hole 2 and rod 3, and having at their outer ends the heads 7 which are shown to be approximately elliptical or elongated in a plane cutting the rod 3 transversely at right angles. 40 For each trunnion a rein 8 is provided having at its lower end the trunnion support 9 whose eye or opening 10 is elongated longitudinally of the rein, of vertically considering the rein to be suspended vertically in 45 use as shown. The width, or horizontal or transverse dimension of the eyes 10 is slightly less than the shorter axis or width of the heads 7. The length or vertical dimension of the eyes 10 is somewhat larger than

the longer axis of the heads, and the longer 50 axis of the heads is somewhat larger than the width of the eyes 10.

The trunnion supports can be readily assembled with the trunnions by turning the supports 9 so that the longer axes of the 55 eyes 10 will register with the longitudinal axes of the heads. Then the supports can be readily slid over the heads 7 and the supports 9 turned 90° on the trunnions when they will occupy the relative positions 60 shown. The elongated portions of the heads 7 overlap the outer faces of the supports 9 and prevent their accidental detachment from the trunnions. It is readily seen that by turning the supports 90° from the positions shown they may be readily slid off from the trunnions.

The reins 8 are in use normally attached to one end of a walking beam while the rod 3 has its lower end connected to a pumping 70 means. The reins 8 are shown as ropes but they may be rods. The bearings 9 may be variously made, the particular construction thereof and their mode of connection with the rods or ropes on which they are suspended not forming a novel part of this 75 invention.

I claim:—

In a polished rod operating device, a pair of suspension means each having vertically 80 elongated eyes, a body having a vertical hole therein for a polished rod, means carried by the body for clamping the rod to the body, horizontal trunnions projecting from opposite sides of the body and seated in the lower 85 ends of the said eyes, and heads on the trunnions beyond the outer faces of the suspension means, the vertical dimension of heads being not greater than the width of the eyes and the horizontal dimension of the heads 90 being greater than the width of the eyes and not greater than the length thereof, the heads overlapping the suspension means at both sides of the eyes.

In testimony whereof I hereunto affix my 95 signature.

JOSEPH R. MAHAN.
